WIRE BRUSH MOUNTING

Rudolph R. Radinse, Avon Lake, Ohio

Application September 4, 1934, Serial No. 742,644

2 Claims. (Cl. 15—179)

This invention relates to wire brush mountings and in particular to the method of assembling the wire brush with the mountings.

An important object of the invention is to provide means whereby a brush may be clamped between a pair of flanged mountings in such a manner as to be irremovable, except by destroying the mountings.

Another object of the present invention is to provide a connecting means between the flanged mountings which acts as a bearing for the brush and also as a clamping means for both mountings.

Other objects and advantages may be noted from the following specifications and their accompanying illustration, in which:—

Fig. 1 is perspective view of a brush secured between a pair of mountings.

Fig. 2 is a sectional view of the device. Fig. 3 is an enlarged fragmentary view of the device showing one of the flanged mountings and the method of securing the sleeve to the mounting.

Fig. 4 is a plan view of the mounting and the sleeve assembly.

Referring more particularly to the drawing, 10 indicates an annular mounting plate flanged inwardly at 11 and again embossed inwardly at 12, the surface of flange 12 forming a bearing surface for the brush when in use, as when the brush is mounted on a rotary shaft.

Between the mounting or side plates 10 is attached a connecting member in the form of a sleeve, the edges of which are contracted or bent inwardly as shown at 14 and 15 to contact the embossed portions 11 of the respective mounting plates 10. This connecting sleeve forms a

bearing surface 13 to accommodate the brush 16, said brush being superimposed over the connecting sleeve, after which the second mounting plate is pressed or inserted in the opening 17 of the sleeve 13, thus confining and clamping the brush in its assembled form.

After the brush is thus assembled an expanding tool of a proper kind (not shown) is inserted in the embossed portion 11 of the plates 10 and expanded. This expands the metal, 10 forming a series of struck up or beaded portions 18 around the diameter of the embossed portion 11 of the mounting 10, and the metal thus expanded forms a locking means for the sleeve 13 and thus locks the brush in the assembled position.

It will thus be seen that I have provided a very simple, quick and convenient means for clamping a brush in a mounting, and the mounting is so constructed that it is practically impossible for it to separate, and thus the brush is positively clamped in position.

I claim:

1. A brush comprising a pair of side plates, a boss on the inner side of each side plate, said boss having a central opening and an inwardly projecting circular flange around said opening, forming a bearing, a sleeve between the plates, said sleeve having inturned ends rigidly engaged with the periphery of the boss, and brush material clamped between the plates.

2. A brush as in claim 1, the periphery of the boss having beaded portions in locking engagement with the inturned ends of the sleeve and serving to hold the side plates clamped against the brush material.

RUDOLPH R. RADINSE.
